FLUID DISPLACEMENT PUMP

Filed April 9, 1928

UNITED STATES PATENT OFFICE

EDWARD F. McCARTHY, OF CHICAGO, ILLINOIS, ASSIGNOR TO CHICAGO PUMP COMPANY, OF CHICAGO, ILLINOIS, A CORPORATION OF ILLINOIS

FLUID-DISPLACEMENT PUMP

Application filed April 9, 1928. Serial No. 268,699.

This invention relates to fluid displacement pumps in which a liquid is caused to be moved through a plurality of tanks, filling them and emptying them at predetermined intervals and thereby displacing the air or gases entering the apparatus. The principal object of the invention is to provide a fluid displacement device which may be used to produce partial vacuum or pressure.

Another object is to handle either gaseous or liquid fluids and to effect a separation of the fluids and to expel the gases and liquids from the apparatus through separate discharge outlets. Another object is to utilize the discharge of liquids from superimposed tanks to create vacuum therein into which space air or other gas is forced by liquid entering the tank and filling the space therein, whereby the gaseous and liquid fluids may be moved through the apparatus and the liquid pumped back into a boiler or other receptacle free from the gaseous fluid. This device combined with a steam heating system provides an ideal method of purging the system of air, gases and water and returning the water freed from the air and gases to the boiler, if desired.

The invention consists, therefore, in a fluid displacement pump embodying a plurality of superimposed intercommunicating tanks, the lowermost one of which has an inlet for gaseous and liquid fluids, and the upper one of which has one or more discharge outlets, together with associated valve mechanism whereby the liquids are discharged intermittently from one tank to the other by gravity and the air or gases thereby moved into the tank from which the liquid was discharged. Pumping means for elevating the liquid from the lowermost tank to the uppermost one is provided whereby the operation of the apparatus is made continuous.

It further consists in the several novel features of construction, arrangement and

combination of parts hereinafter fully set forth and claimed.

The invention is clearly set forth in the accompanying drawing in which—

Figure 1 is a vertical longitudinal section through a fluid displacement pump embodying a simple form of the present invention; 50

Fig. 2 is a plan thereof;

Fig. 3 is a detailed end view of certain valve actuating mechanism; and

Fig. 4 is a horizontal section taken on the 55 line 4—4 of Fig. 1.

Referring to the drawing which illustrates one embodiment of invention, the reference character 1 designates a bottom tank, 2 an intermediate tank and 3 an upper tank through which liquid is moved from the upper tank through the intermediate one to the bottom tank at predetermined intervals, thereby displacing gas or air contained in said tanks, and creating a vacuum or pressure. As a preference, the intermediate tank is larger than the upper and bottom tank, and, if desired, the lower tank 1 may be larger than the upper tank 3, the tanks being so proportioned that the circulating liquid will substantially fill the various tanks at predetermined intervals and provide a constant flow of liquid through a water pump 4, which is used for elevating the liquid from the bottom tank to the upper one. 60 65 70 75

The inlet of the pump 4 is connected to the bottom tank 1 by an inlet pipe 5, and its discharge end is connected to the upper tank by a discharge pipe 5^a. The bottom tank is provided with an inlet opening 6 which is controlled by an inwardly opening check valve 14 which permits fluids to enter the bottom tank through the inlet opening 6, 80 85 but prevents the escape of fluids from the tank through said opening.

Between the tanks 1 and 2 is a port 10^a controlled by a valve 10, through which port liquid discharges from the intermediate tank 90

2 into the bottom tank 1 at predetermined intervals, and between the upper tank 3 and intermediate tank 2 is a port 11^a controlled by the valve 11, through which port liquid is discharged from the upper tank 3 into the intermediate tank at intervals. The opening and closing of the valves 10 and 11 is so timed that when one of the valves is opened, the other is closed.

10 The valves 10 and 11 are operated by mechanism, here shown as comprising float mechanism 9 contained in the intermediate tank 2, and having a lost motion mechanism whereby the intermediate tank 2 is caused to be filled and emptied of liquid at intervals. The float mechanism, as shown, comprises a ball float 19 mounted upon a forked arm 20 fulcrumed upon a shaft 21, and weighted arms 9^a are also fulcrumed on the shaft 21. The arms 9^a have pins 9^b on their ends which enter slots in the forks of the arms 20 and are arranged to be engaged by the ends of said slots. Adjustment screws are secured in the arms 20 at the ends of the slots and afford means for regulating the effective ends thereof.

15 The valves 10 and 11 are connected by a rod 22 which has a lost motion connection with the float mechanism, which, as shown, comprises pins 23 on the rod 22 and entering slots in the weighted arms 9^a. It will be observed that the ball float 19 has a wide range of movement and only opens and closes the valves 10 and 11 at the limits of its strokes. The valves 10 and 11 are of sufficient size to permit the liquid to discharge from one tank into another more rapidly than it can be handled by the pump 4. Between the tanks are gas ports 15^a and 16^a controlled by upwardly opening check valves 15 and 16. The check valves remain seated until forced open by the pressure in a lower tank when it exceeds that in the tank above the valve.

20 In the upper tank 3 is a liquid discharge port 8^a and a gas discharge port 7^a controlled by float operated valves 8 and 7. As shown, the valves 8 and 7 are connected to a float lever 13 pivotally supported from one wall of the tank and having a ball float 17 upon its free end. The valves 8 and 7 are so arranged that when one closes the other opens and vice versa. When the ball float rises to a high place, it opens the valve 8 and permits surplus liquid to be discharged from the tank 3, and when the ball float occupies a low position, it opens the valve 7, thereby permitting the gas to escape from the tank 3 when the tank fills 25 with liquid.

65 The apparatus may be used for creating a vacuum or for building up pressure. It may be employed as a vacuum pump for steam heating systems, in which case the inlet 6 is connected to the return pipe of the

system and the discharge 8^a is connected to the boiler, or some other receptacle into which it is desired to discharge the liquid.

70 In the operation of the apparatus, the intermediate tank is filled with liquid and when the ball float 19 rises to its upper limit, it closes the valve 11 and opens the valve 10, thereby permitting the liquid in the intermediate tank 2 to discharge into the lower tank 1 and causing a partial vacuum in 75 the tank 2 which is relieved by the gases (entering the same through the valve 15) which are being forced out of the lower tank 1 by the liquid entering said lower tank. The pump 4 being in operation, it 80 discharges liquid from the lower tank 1 into the upper tank 3, but not as rapidly as the lower tank is being filled.

85 When the intermediate tank 2 is emptied, the float mechanism closes the valve 10 and opens the valve 11, thereby permitting the liquid in the tank 3 to discharge into the intermediate tank. With the valve 10 and the check valve 15 closed, and the pump 4 continuing to discharge the liquid from the 90 lower tank into the upper one, a partial vacuum is created in the lower tank and fluids enter said tank through the inlet 6. As the liquid from the upper tank 3 discharges into the intermediate tank 2 and 95 fills the latter, the gases in the intermediate tank are being forced through the check valve 16 into the upper tank 3 and escape through the gas outlet 7^a as the liquid coming from the tank 1 through the pump 4 100 fills the upper tank 3.

95 In the event any surplus liquid enters the lower tank 1 through the inlet 6, it may cause the upper tank to become filled before the intermediate tank 2 is emptied, 105 thereby causing the ball float 17 in the upper tank to rise and close the valve 7 and open the valve 8, and thereby permitting the surplus liquid to be discharged from the upper tank 3 through said valve 8. Whenever the remaining liquid in the upper tank is discharged into the intermediate tank, the ball float 17 closes the valve 8 and opens the valve 7, thereby permitting any gases entering the upper tank 8 to escape. As 110 the liquid fills the intermediate tank 2, the float valve 19 is raised, the valve 11 closed and the valve 10 opened, thereby permitting the liquid to discharge from the intermediate tank into the lower one and repeating 115 the operation above described, which is carried on continuously during the operation of the apparatus.

120 I claim as new, and desire to secure by Letters Patent:

125 1. A fluid displacement pump comprising in combination a plurality of superimposed tanks intermittently filled with liquid which is discharged from one tank into the other by gravity, whereby gas contained in a low- 130

er tank is discharged therefrom and admitted into a higher one, there being an inlet to the lower tank and a discharge from the upper tank, a float valve controlled port between an upper and lower tank through which the liquid discharges at predetermined intervals from a higher tank into a lower one by gravity, a valve controlled gas port through which gas is admitted at predetermined intervals from a lower tank to a higher tank when expelled from a lower one by liquid entering the lower tank, and pumping means having its inlet connected to the lower tank and its discharge connected to the higher tank for elevating the liquid from the lower one into the higher one.

2. A fluid displacement pump comprising in combination a plurality of liquid and gas receiving tanks disposed at different elevations, the lowest tank having an inlet and the highest one having a discharge outlet, float valve controlled means between said tanks responsive to variations of the level of the liquid in one of the tanks for discharging at predetermined intervals the liquid contained in a higher tank into a lower one by gravity, whereby a partial vacuum is produced in a higher tank, valve controlled means whereby gas contained in a lower tank is admitted to a higher tank when displaced by the liquid entering the lower tank from the higher tank, and pumping means for elevating liquid from the lower tank to the higher one and having its inlet connected to the lower tank and its discharge connected to the higher one.

3. A fluid displacement pump comprising in combination a plurality of liquid and gas receiving tanks disposed at different elevations, the lowest tank having an inlet and the highest one a discharge outlet, float valve controlled means responsive to variations of the level of the liquid in one of the tanks for discharging liquid contained in a higher tank into a lower one by gravity, whereby a partial vacuum is produced in a higher tank and gas contained in a lower tank is displaced from said lower tank, there being a valve controlled gas port between the higher and lower tanks through which the gas is expelled from a lower tank into an upper one, and pumping means for elevating liquid from a lower tank into a higher one, and having its inlet connected to said lower tank and its discharge connected to the higher tank.

4. A fluid displacement pump comprising in combination a plurality of liquid and gas receiving tanks disposed at different elevations, the lowest tank having a valve controlled inlet and the highest one having a valve controlled discharge outlet, float valve mechanism between said tanks responsive to variations of the level of the liquid in one of the tanks for discharging at predetermined

intervals the liquid contained in a higher tank into a lower one by gravity, whereby a partial vacuum is produced in a higher tank, valve controlled means whereby gas contained in a lower tank is admitted to a higher tank when displaced by the liquid entering the lower tank from the higher tank, and pumping means for elevating liquid from the lower tank to the higher one and having its inlet connected to the lower tank and its discharge connected to the higher one.

5. A fluid displacement pump comprising in combination a plurality of liquid and gas receiving tanks disposed at different elevations, the lowest tank having a check valve controlled inlet and the highest one having a float valve controlled gas discharge outlet and a float valve controlled liquid discharge outlet, the one valve being open when the other is closed and vice versa, valve controlled means responsive to variations of the level of the liquid in one of the tanks for discharging at predetermined intervals the liquid contained in a higher tank into a lower one by gravity, whereby a partial vacuum is produced in a higher tank, valve controlled means whereby gas contained in a lower tank is admitted to a higher tank when displaced by the liquid entering the lower tank from the higher tank, and pumping means for elevating liquid from the lower tank to the higher one and having its inlet connected to the lower tank and its discharge connected to the higher one.

6. A fluid displacement pump comprising in combination a plurality of liquid and gas receiving tanks disposed at different elevations, the lowest tank having an inlet and the highest one having a discharge outlet, float valve mechanism between said tanks responsive to variations of the level of the liquid in one of the tanks for discharging at predetermined intervals the liquid contained in a higher tank into a lower one by gravity, whereby a partial vacuum is produced in a higher tank, valve controlled means whereby gas contained in a lower tank is admitted to a higher tank when displaced by the liquid entering the lower tank from the higher tank, and pumping means for elevating liquid from the lower tank to the higher one and having its inlet connected to the lower tank and its discharge connected to the higher one.

7. A fluid displacement pump comprising in combination a plurality of liquid and gas receiving tanks disposed at different elevations, the lowest tank having an inlet and the highest one having a discharge outlet, float valve mechanism between said tanks having a lost motion connection between the valve and its float, said float valve controlled means being responsive to variations of the level of the liquid in one of the tanks

for discharging at predetermined intervals the liquid contained in a higher tank into a lower one by gravity, whereby a partial vacuum is produced in a higher tank, valve controlled means whereby gas contained in a lower tank is admitted to a higher tank when displaced by the liquid entering the lower tank from the higher tank, and pumping means for elevating liquid from the lower tank to the higher one and having its inlet connected to the lower tank and its discharge connected to the higher one.

8. A fluid displacement pump comprising in combination a lower tank, an intermediate tank and an upper tank, the lower tank having a valve controlled inlet and the upper one having float controlled gas and liquid ports, one of which is closed while the other is opened and vice versa, valve controlled liquid ports between the several tanks responsive to variations of the level of the liquid in one of the tanks, the valve of one of said valve controlled ports being opened while the other is closed and vice versa, and valve controlled gas ports between the several tanks whereby when a liquid port is opened liquid is discharged from the higher tank into a lower tank and gas is admitted into a higher tank from a lower one, and pumping means having its inlet connected to the lower tank and its discharge connected to the upper tank and operating to pump liquid from the lower tank into the upper one.

35. 9. A fluid displacement pump comprising in combination a lower tank, an intermediate tank and an upper tank, the lower tank having a valve controlled inlet and the upper one having a valve controlled port, float valve controlled liquid ports between the several tanks responsive to variations of the level of the liquid in the intermediate tank, the valve of one of said valve controlled ports being opened while the other is closed and vice versa, and valve controlled gas ports between the several tanks whereby when a liquid port is opened liquid is discharged from the higher tank into a lower tank and gas is admitted into a higher tank from a lower one, and pumping means having its inlet connected to the lower tank and its discharge connected to the upper tank and operating to pump liquid from the lower tank into the upper one.

55. 10. A fluid displacement pump comprising in combination a lower tank, an intermediate tank and an upper tank, the lower tank having a valve controlled inlet and the upper one having a float valve controlled gas port and a float valve controlled liquid port, the one being open while the other is closed and vice versa, float valve controlled liquid ports between the several tanks responsive to variations of the level of the liquid in the intermediate tank, the valve

of one of said liquid ports being open while the other is closed and vice versa, and check valve controlled gas ports between the several tanks whereby when a liquid port is opened liquid is discharged from the higher tank into a lower tank and gas is admitted into a higher tank from a lower one, and pumping means having its inlet connected to the lower tank and its discharge connected to the upper tank and operating to pump liquid from the lower tank into the upper one.
